United States Patent Office.

FRANKLIN LEONARD, OF CLEVELAND, OHIO.

Letters Patent No. 78,977, dated June 16, 1868.

IMPROVEMENT IN DIES FOR FORGING EYE-BOLTS.

The Schedule referred to in these Letters Patent and making part of the same.

TO ALL WHOM IT MAY CONCERN:

Be it known that I, FRANKLIN LEONARD, of Cleveland, in the county of Cuyahoga, and State of Ohio, have invented certain new and useful Improvements in Dies for Forging Eye-Bolts, &c.; and I do hereby declare that the following is a full and complete description of the same, reference being had to the accompanying drawings, making part of this specification, in which—

Figure 1 is an end view of the machine.

Figure 2, a top view.

Figure 3, detached dies.

The other figures will be referred to.

Like letters of reference refer to like parts in the different views.

A, fig. 1, represents a block or base, on the top of which are secured the dies B C. In the face of each die is sunk the form of the eye of the bolt-rings D, Figure 5, one-half the thickness in each die, which, on being placed upon each other, as shown in fig. 1, conform relatively to each other, forming a matrix, in which the ring is shaped. E, fig. 3, is a semispherical hollow, sunk in the face of the die C, which is the upper section. In the lower section, B, is a corresponding hollow, E', in the bottom of which is a hole, a, penetrating in the die, thence down into the block, as indicated by the dotted lines a', fig. 1. G is a pedal, pivoted in the block, one end of which reaches inward through beyond the hole a, the purpose of which will hereafter be shown.

The practical use of this machine is for forging rings or eye-bolts, so that the eye or ring shall be without a joint, forging them from one solid piece, thereby producing a stronger ring than those made in the ordinary way, which is done by taking a piece of rod, of the proper size and length, and then bevelling one end into a loop or eye. These rings, in consequence of the end not being welded, or in any way secured, are liable to spread if much strain is exerted upon them; hence they are not safe for purposes where great strength is required; or if, in some cases, the end is welded to the stem of the bolt, the labor of welding is a matter of much time, and hence expense. This is not the case with rings made in this machine, they being made out of a solid head, in much less time, and better and cheaper, in the following manner, viz: I take a piece of rod, of the proper size and length, as represented in fig. 6, one end of which is then heated, and the other inserted in the hole a. Enough of the rod projects above the face of the die to form a head, which, on being upset, is rounded and shaped by the hollows E E'. This being done, the heated rod is then pushed from the hole by means of the pedal above referred to. A rod thus headed is shown in Figure 4, which, while it is yet hot, is slightly flattened by a blow from a hammer, and then placed in the die D. The upper section, C, is now closed upon it, and the head therein made to assume the shape of the dies by a few blows given upon the top of the upper section, thus forming a jointless ring or loop from the solid head, as shown in fig. 5.

What I claim as my improvement, and desire to secure by Letters Patent, is—

The dies B C, when constructed and arranged to operate in the manner as and for the purpose specified.
